A. B. Graham,
Attorney.

UNITED STATES PATENT OFFICE.

WILLIAM BARBOUR, OF EVERETT, MASSACHUSETTS.

CARBURETER-ADJUSTER.

1,299,394.

Specification of Letters Patent.

Patented Apr. 1, 1919.

Application filed August 22, 1917. Serial No. 187,626.

To all whom it may concern:

Be it known that I, WILLIAM BARBOUR, a citizen of the United States, and a resident of Everett, in the county of Middlesex and 5 Commonwealth of Massachusetts, have invented certain new and useful Improvements in Carbureter-Adjusters, of which the following is a full, clear, and exact specification.

10 In certain makes of automobiles, it is an exceedingly awkward thing to adjust the carbureter, and especially on those cars whose dash has had a speedometer board applied thereto. On these cars, the chauffeur 15 must frequently stop before it is safe for him to lean over downward and to one side in order to reach and actuate the adjusting rod provided for the purpose.

The purposes of my invention are, first, 20 to provide an adjusting means which the chauffeur can manipulate without danger or inconvenience, and, second, to supply means whereby he can see at a glance the point of adjustment at which the device is set.

25 In the drawings forming part of this specification, Figure 1 is a plan view of portions of an automobile showing my improvements applied thereto. Fig. 2 is a side sectional elevation on the line X—X in Fig. 1. 30 Fig. 3 is a sectional detail view of the adjusting fork and allied parts.

The reference numeral 1 designates the dash of an automobile; 2, the carbureter; and 3, the forked rod for the adjustment of 35 the carbureter valve. Previous to my invention, the rod 3 was prolonged through the dash 2 and formed with a short arm by means of which it was turned. Instead of this, I dispense with such arm, and substi- 40 tute a spur gear or pinion 5 in lieu thereof. An entirely new rod may be used, or if preferred and as would be the case in applying my improvement to a used car, I cut off the upper three or four inches of the rod 3, and 45 splice upon the severed end a suitable length of new rod 3^a bearing the pinion 5, a splicing sleeve 8 having set screws 8^a being provided for the purpose.

A block 4 suitably attached to the dash 1 50 forms the upper bearing for the rod 3 or its prolongation 3^a, and also a support for a rack 6 which meshes with the pinion 5. At the opposite side of the car, is a similar spur gear or pinion 7 meshing with a rack 9, this 55 rack being joined in any suitable manner to

the rack 6, as by a twisted bar 10, to cause them to reciprocate as one.

The rack 9 is slidably supported by a block 11 attached to the dash 1, and the pinion 7 is mounted on the end of a spindle 60 12 rotatable in the block 11. The other end of the spindle turns in suitable bearings, preferably in the plate 16 which is fastened to the visible surface of the speedometer board 13, and the extremity of the spindle 65 has rigidly mounted thereon an indicator 14 provided with an actuating wing 15. The plate 16 being given suitable indicator markings, the rotation of the indicator 14 and of the connected carbureter valve is made vis- 70 ily correlated.

A helical spring 17 pressing between the inner surface of the dial plate 16 and a suitable stop on the spindle 12, creates sufficient friction to keep the spindle and connected 75 parts from undesired motion.

The rod 3 being of well known form, has forks 20 at its lower end designed to loosely enter holes 22 in the valve operating disk 21. I prefer to place in each hole 22 a 80 small thimble 23 kept from dropping down and out therefrom by means of a shoulder 24, the forks 20 being slidable in these thimbles. These thimbles enable lost motion to be taken up and thereby insure that every 85 slight turn of the indicator will correspondingly affect the carbureter valve, and so render the device preferably responsive.

With the type of car for which my improvement is specifically designed, the steering shaft is also directly below the indicator 90 16. Hence, all the chauffeur needs to do in adjusting this carbureter is to drop his eye for a moment to the dial and with his free right hand move the indicator to the 95 degree desired. This he can do without changing his position, or to the slightest extent losing his control of the car.

What I claim is:

1. The combination with an automobile or 100 the like having a carbureter, of an operative shaft rising from the latter, a pinion on the upper end of said shaft, a pinion having a spindle for its support, an indicator carried by said spindle, and an elongated 105 connection between said pinions including rack teeth meshing with each pinion.

2. The combination with an automobile or 110 the like having a carbureter, of an operative shaft rising from the latter, a pinion on the

upper end of said shaft, a rack meshing therewith, a second rack substantially parallel with but separated from the first rack, connection between said racks, a pinion meshing with the second-named rack, a spindle carrying the last-named pinion, an indicator carried by said spindle, and a dial for said indicator.

3. The combination with an automobile or
10 the like having a carbureter, of an operative rod rising from the latter, a dash, a speedometer board spaced from the dash, a dial plate attached to the speedometer board at the side of the car farthest from the carbureter, a spindle passing through said dial plate, an indicator fixed on the end of said

spindle exterior to said plate, a friction spring for said spindle, a block rotatably supporting the other end of said spindle, a pinion mounted on the last-mentioned end of 20 said spindle, a rack meshing with said pinion and slidably supported by said block, a block rotatably receiving said rod, a pinion mounted on said rod, a rack slidably supported by said block and meshing with said 25 pinion, and a twisted bar uniting said racks, whereby a turn of said indicator adjusts the carbureter.

In testimony that I claim the foregoing invention, I have hereunto set my hand this 30
20th day of August, 1917.

WILLIAM BARBOUR.
